FIG. 1 is a top perspective view of a sliding overcap for dispensing container in accordance with my new design;
 FIG. 2 is a top plan view thereof, wherein a bottom plan view thereof is identical;

FIG. 3 is a front elevational view thereof, wherein a rear elevational thereof is identical; and,

FIG. 4 is left side elevational view thereof, wherein a right side elevational view is identical.

The broken lines in the figures are for the purpose of showing unclaimed environmental structure only and form no part of the claimed design.
